JAMES F. McELROY, DECEASED, ASSIGNOR TO CONSOLIDATED CAR-HEATING COM-
PANY, A CORPORATION OF WEST VIRGINIA.

CASING FOR ELECTRIC SWITCHES.

1,207,956.

Specification of Letters Patent. Patented Dec. 12, 1916.

Application filed August 29, 1911. Serial No. 646,607.

To all whom it may concern:

Be it known that I, JAMES F. McELROY, a citizen of the United States, residing at Albany, county of Albany, State of New York, have invented certain new and useful Improvements in Casings for Electric Switches, the following being a full, clear, and exact disclosure of the one form of my invention which I at present deem preferable.

For a detailed description of the present form of my invention, reference may be had to the following specification and to the accompanying drawings, which illustrate my invention.

Figures 1 and 2 represent the invention as a partition-switch, Fig. 1 being a front view thereof with the casing in section and Fig. 2 a vertical section through the partition; Figs. 3, 4 and 5 represent the invention arranged as a wall-switch, Fig. 3 being a front view thereof with the casing in section, Fig. 4 a vertical section, and Fig. 5 a bottom elevation thereof.

The present invention relates specifically to switches of the push-button type, designed particularly for electric circuits controlling the door motors of a railway car. The switch is, for this purpose, located at the end of the car so as to be conveniently operated by the motorman on the car platform. I have shown the invention arranged as a partition-switch along the lines of the partition-switch shown in my pending application for patent Ser. No. 643,576, filed August 11, 1911, this being the form in which the same is now being used on the Pennsylvania railway. I have also shown the invention arranged as a wall-switch, this being the form in which it is now used on the elevated railways at Boston. In the present application I do not intend to make claim to the particular features which pertain to its partition-switch form since such features constitute the subject matter of my aforesaid application Ser. No. 643,576, but the present application is directed specifically to the wall form of switch, although the broader features herein claimed are applicable to both forms.

Referring particularly to Figs. 1 and 2, A represents the end wall of a car, or other apartment, which, in this instance, serves as

a partition between the different portions of the switch which is located in an opening in the said wall, being operated from a point forward of the said wall, but accessible from the rear of the wall where it is provided with the usual cover, and provided also with an opening to receive the conduit containing the leading-in wires. The casing of the switch is indicated generally at B and it is arranged to contain a plurality of push-button switches. It is seated in an opening in the wall A, being provided with seating flanges b^2 which are screwed to the wall. On the forward or operating side the casing B is provided with an overhanging hood b^1 and also with an outer wall b separated a slight distance from the main wall of the casing. The said hood and supplementary wall afford protection against the entrance of water into the casing through the button holes and afford a drip device for the removal of any water which may come against the switch casing in its exposed position. The supplementary wall b also affords an extra bearing for the push-buttons C which pass through openings in both the main and the supplementary walls. Each push-button C is provided with an enlarged end inside the case, in which end is molded a small steel wearing plate c. This steel plate bears upon one end of the copper bolt D¹ which passes through a tubular guide D⁴ seated on the insulating base E. Surrounding the tubular guide is a helical spring D³, one end of which is seated upon the bottom flange of the guide while the other bears against a copper disk D inserted under the head of the bolt D¹. The disk D serves as the movable contact-member of the switch and is loosely mounted on the bolt D¹ and will thereby rotate on the bolt D¹ so that a fresh contact surface may be presented from time to time to the stationary contact members. The stationary contact members are the metal posts D² secured to the insulating base E and provided with binding screws on the rear side of the said base for establishing connection with the leading-in wires. One contact post D² serves as a common contact for all of the four disks D of the four respective switches contained in the casing, and for this purpose it is located centrally with respect to these four disks D, so that

each disk can make contact therewith. The individual contact posts D^2 of the respective switches are located under the outer edges of the respective disks D and nearly opposite the central one to balance the pressure against the disks D . It is manifest that if the button C at either of the four switches is pushed in, the steel-wearing plate c in the push-button will bear against the head of the bolt D^1 and force it in against the outward pressure of the spring D^3 until the disk D comes in contact with the central post D^2 at one edge and the individual contact post D^2 at the opposite edge of the disk, thereby closing the circuit between the two posts. The insulating base E is located approximately midway of the casing B and divides the casing into front and back compartments, the switch members being mounted on the said base in the forward part of the casing. The rear portion of the casing extends through the partition A and on the rear side of said partition it is provided with a detachable cover B^1 which is separated from the base E a sufficient distance to form a junction-box in rear of the said base E . The casing is also provided, in rear of the partition, with an opening for the conduit B^2 which carries the leading-in wires, the outer edge of this opening being closed when the detachable cover B^1 is applied to the rear side of the casing.

In assembling my device the rear cover B^1 being removed, the push-buttons C , will first be passed through the openings provided for them in the front wall of the casing and the supplementary wall b . Then the insulating base E with the switch members mounted thereon will be placed in position, the heads of the bolts D^1 bearing upon the steel plates c of the push-button and the base will then be secured to its seating flanges within the casing. Applying my switch to the partition-wall A , the front or forward section of the casing will be passed through the partition from the rear until the seating flanges b^2 bear against the rear side of the wall and are secured thereto by screws. Then the conduit B^2 with the leading-in wires projecting from its upper end will be placed in position in the opening or notch formed for its reception in the rear end of the casing. The leading-in wires will then be attached to the several contact posts D^2 and, after the switch has been tested, the rear cover plate B^1 will be applied and will serve at the same time to close the casing and to retain in place the conduit B^2 .

Turning to Figs. 3, 4 and 5, it will be readily understood that the push-buttons C and the internal arrangements within the casing are the same as those shown in Figs. 1 and 2. The casing itself is, however, arranged somewhat differently. The hood portion b^1 is formed as a separate casting

which will be independently secured to the wall against which the switch is to be applied, and will be the part which is first secured to the wall. The casing itself is formed, as in the previous case, of two parts 76 or sections, to-wit, the rear part B which in this instance is seated upon and secured to the wall after the hood portion b^1 is in place, and the forward part B^1 which is hinged to the part B by the hinge F . The 75 insulating base E which carries the switch members is mounted upon and secured to the forward part of the casing B^1 in the manner heretofore described. The part B^1 , together with the base E and switch members assembled therewith, will then be placed in position upon the part B and secured thereto by the rivet at the hinge F . This permits the said portion B^1 and the parts mounted thereon to swing forward on the 80 hinge F to permit the attachment of the portion B upon the wall or for the connection of the leading-in wires to the contact parts D^2 , which wires enter the casing from the conduit B^2 which is passed through a 85 tubular opening in the lower portion of the part B . The curve of the hood b^1 is so shaped as to permit the above-mentioned swinging of the portion B^1 upon its hinge F .

The form of my device shown in Figs. 1 and 2 contains only four push-button switches, whereas the form shown in Figs. 3, 4 and 5 contains six. In the former case the four push-buttons will control the middle door and one end door on one side of a 100 railway car, two of the buttons being pushed to open the doors, and the other two to close them, only a momentary contact being required to set the doors in motion. Obviously either one or both of the two doors 105 referred to can be operated, and, in case both doors are operated, they can be opened or closed simultaneously, since the two buttons involved in the operation are so close together that the operator can push both of them at once. In the arrangement which contains six buttons, three of them will serve for the opening, and the other three for the closing of each and all of the three doors on one side of the car, to-wit, the central door and the two end doors. In this case also the doors may be operated individually or together and, if desired, simultaneously.

What I claim as new and desire to secure 120 by Letters Patent is:

1. A switch casing having a cover and an external supplemental wall spaced from said cover and parallel therewith, said cover and said wall being provided with aligned openings forming push button guiding means.

2. A switch casing having a cover and an external supplemental wall spaced from said cover and parallel therewith, said cover and said wall being provided with aligned open-

ings forming push button guiding means, and a hood overhanging the external wall and the push button openings.

3. A switch casing having a cover and an external supplemental wall spaced from said cover and parallel therewith, said cover and said wall being provided with alined openings forming push button guiding means, and a separable hood overhanging said cover and said external wall.

4. A switch casing formed of stationary and movable members hinged together, said members having means for clamping a conduit for the leading-in wire, and a base secured to the movable member and provided with means for supporting stationary and movable switch members.

5. A switch casing formed of stationary and movable members hinged together, and a base secured to the movable member and provided with means for supporting stationary and movable switch members, one of said switch members having main and supplemental walls, the latter serving as a shield for the former.

6. A switch casing formed of stationary and movable members hinged together, and a base secured to the movable member and provided with means for supporting stationary and movable switch members, and a hood overhanging the movable section.

7. An electric switch comprising a casing having separable front and back sections, said sections being provided with means for

clamping a wire conduit between them, one of the sections being fixed and the other section being movable, a base attached to the front section and dividing the casing into two compartments and provided with means for supporting stationary and movable contacts.

8. An electric switch having front and rear casing sections, one fixed and one movable, said sections being provided with means to clamp a conduit for the leading-in wires, an insulating base carried by the front section and dividing the casing into front and rear compartments, said base being provided with means for supporting stationary and movable switch members in the front section, and the wall of said front section being provided with means for supporting switch operating mechanism.

9. An electric switch comprising a casing having a front wall and a supplementary shielding wall spaced from the front wall, the space between said walls being open at the bottom, said walls being provided with alined guide openings, and a hood overhanging the wall and the switch operating means.

In witness whereof I have hereunto set my hand, before two subscribing witnesses, this 26th day of August, 1911.

JAMES F. McELROY.
